(57) **CLAIM**

The ornamental design for a wall-mounted soap dispenser, as shown and described.

DESCRIPTION

FIG. 1 is a perspective view of a wall-mount for soap dispensers, in an exploded configuration, showing our new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The broken line showing of a box is for the purpose of illustrating portions of the wall-mounted soap dispenser that form no part of the claimed design.
